UNITED STATES PATENT OFFICE.

HENRY I. WRIGLEY, OF CHICAGO, ILLINOIS, ASSIGNOR TO UNIVERSAL DRAFT GEAR ATTACHMENT CO., OF CHICAGO, ILLINOIS, A CORPORATION OF ILLINOIS.

DRAFT-GEAR YOKE.

1,164,695.

Specification of Letters Patent. Patented Dec. 31, 1915.

Application filed August 16, 1913. Serial No. 735,054.

To all whom it may concern:

Be it known that I, HENRY I. WRIGLEY, a citizen of the United States, and resident of Chicago, county of Cook, and State of Illinois, have invented certain new and useful Improvements in Draft-Gear Yokes, of which the following is a specification, and which are illustrated in the accompanying drawings, forming a part thereof.

10 The invention relates to that type of draft yokes which forms the subject of an application for Letters Patent by Bernie J. Bernuharl, Serial No. 774,628, filed June 19, 1913, one of the objects of the invention being to 15 provide for the interlocking of the coupler-engaging or filler block with the yoke in such manner as to resist the tendency of the block to turn or tilt upwardly at its rearward end under pulling stresses; another 20 object being to secure a wedging action for forcing the butt of the coupler into engagement with the top of the yoke socket. These objects are attained by the construction hereinafter described and shown in the accompanying drawings, in which—

Figure 1 is a detail side elevation of the yoke and coupler, partly in section; Fig. 2 is a plan view of the same, partly in section; Fig. 3 is a perspective of the filler block; 30 and Fig. 4 is a detail longitudinal section showing the parts in process of assembling.

The body of the yoke may be of the conventional M. C. B. type, as shown having the top and bottom longitudinal members 35 10, 11, and a suitable rear end 12. The forward end of the upper member of the yoke is offset downwardly to form a shoulder 13 for engagement by the shoulder 14 on the upper side of the butt of the coupler 15. The 40 lower member 11 of the yoke is offset downwardly, as shown at 16, the offset occurring back of the plane of the rear end of the coupler butt when the latter is in its normal position within the yoke. Side plates 17, 18, 45 unite the forward ends of the top and bottom members of the yoke.

The filler block 19 fits within the head of the yoke, being seated upon the downwardly offset portion 16 of its lower member and 50 bearing upon its upper face, which is preferably in line with the upper face of the lower yoke member, the butt of the coupler. At its forward end the filler block is pro-

vided with a backwardly facing upstanding shoulder 20 for engaging the lower shoulder 55 of the coupler butt.

The shoulder 21 formed by the downward offset of the lower member of the yoke is transversely recessed, as shown at 22, and the inner end of the filler block 19 is provided with a toe 23 for entering this recess. Key apertures are formed in the side walls 17, 18, and in the filler block 19 to receive a key 24 which holds the filler block in place and transmits pulling stresses from the coupler to the lower member of the yoke. The key 24 is preferably headed at one end and apertured at the opposite end to receive a cotter pin 25.

The upper face of the offset portion 16 of the lower yoke member is preferably slightly inclined downwardly, as shown, toward its forward end; and the lower face of the block is correspondingly inclined. As the block is forced to its seat it therefore wedges the butt 75 of the coupler upwardly toward or against the top of the yoke socket.

In assembling the parts the butt of the coupler is first inserted into the throat of the yoke and raised to bring its shoulder 14 into engagement with the shoulder 13. The filler block is next inserted under the butt of the coupler, bringing its shoulder 20 into engagement with the coupler shoulder and its toe 23 into the recess 22 and its key aperture 80 into line with the key apertures in the side plates 17, 18, and wedging the coupler butt upwardly. The key now being inserted, the parts are securely locked together. Pulling stresses applied to the shoulder 20 of the 85 filler block are communicated to the yoke through the key 24. As the shoulder is above the key there is a tendency to turn the filler block about the key as a pivot. This tendency is resisted by the forward end of 90 the downwardly offset portion 16 of the lower yoke member, and also by the engagement of the toe 23 within the recess 22. An orifice 26 is formed at the inner end of the 95 recess 22 for the convenient insertion of a tool for the purpose of driving the block 19 from its seat; preferably, however, the toe 23 is provided with an extension 27 which projects through this aperture, and upon which a hammer may be used for dislodging 100 the block. For the purpose of avoiding ex-

cessive weight the filler block 19 may be recessed, as shown in Fig. 3, eliminating metal not required to insure adequate strength.

I claim as my invention.

5 1. In combination, a yoke having a socketed end for receiving the butt of a coupler and a filler block, the bottom of the yoke being offset downwardly at the forward end and being formed with a recess at 10 the inner end of the offset, a filler block seated within the socket of the yoke and having a toe fitting within the recess, and a key securing the block within the yoke.

2. In combination, a yoke having a 15 coupler-receiving socket at its forward end and a gib at the top of the socket, the bottom of the yoke being offset downward at its forward end and having a recess at the rearward end of the offset, a filler block 20 seated within the offset portion of the yoke and having an upstanding gib at its forward end and a toe at its rearward end fitting within the recess, and means for locking the block to the yoke.

25 3. In combination, a yoke having a coupler-receiving socket at its forward end and a gib at the top of the socket, the bottom of the yoke being offset downward at its forward end and having a recess at the rear- 30 ward end of the offset, a filler block seated within the offset portion of the yoke and having an upstanding gib at its forward end and a toe at its rearward end fitting within the recess, and a key setting through 35 the side walls of the socket and the block.

4. In combination, a yoke having a 40 socketed end for receiving the butt of a coupler and a filler block, the bottom of the yoke being offset downwardly at the forward end and being formed with a recess at 45 the inner end of the offset, a filler block seated within the socket of the yoke, means for holding the rearward end of the block against upward movement, and a key securing 50 the block within the yoke.

5. In combination, a yoke having a 55 socketed end for receiving the butt of a coupler and a filler block, the bottom of the

yoke being offset downwardly at the forward end, the upper face of the offset portion being inclined downward toward its forward end, a filler block seated within the socket and having its lower face inclined upward from its forward end, and means for securing the block within the yoke. 55

6. In combination, a yoke having a socketed end for receiving the butt of a coupler and a filler block, the bottom of the yoke being offset downwardly at the forward end and being formed with a recess at 60 the inner end of the offset, the inner wall of the recess being apertured, a filler block seated within the socket of the yoke and having a toe fitting within the recess, and a key securing the block within the yoke. 65

7. In combination, a yoke having a 70 socketed end for receiving the butt of a coupler and a filler block, the bottom of the yoke being offset downwardly at the forward end and being formed with a recess at 75 the inner end of the offset, the inner wall of the recess being apertured, a filler block seated within the socket of the yoke and having a toe fitting within the recess, such toe having a projection extending through the aperture, and a key securing the block within the yoke.

8. A yoke having a socketed butt-receiving end and a butt-retaining shoulder, a 80 filler block housed within the socketed end of the yoke and having a butt-retaining shoulder and being interlocked with the yoke to prevent transverse inward movement, and means for securing the block to the yoke.

9. A yoke having a socketed butt-receiving end and a butt-retaining shoulder, a 85 filler block housed within the socketed end of the yoke and having a butt-retaining shoulder and being interlocked with the yoke to prevent transverse movement and a 90 removable key for securing the block to the yoke.

HENRY I. WRIGLEY.
